ARCHERY BOW

Neil W. Tarbell, Ontario, Calif.
(P.O. Box 244, Upland, Calif.)

Filed Mar. 8, 1962, Ser. No. 69,150

Term of patent 14 years

(Cl. D30—1)

FIG. 1 is a side elevational view with portions thereof being shown in dotted lines;

FIG. 2 is an elevational view as seen from the right of FIG. 1;

FIG. 3 is a side elevational view of the mid-section of the bow body as seen from the side opposite FIG. 1 and shown to an enlarged scale;

FIG. 4 is an elevational view of FIG. 3 viewed from the left thereof;

FIG. 5 is a section taken on the line 5—5 of FIG. 3; and

FIG. 6 is a section taken on the line 6—6 of FIG. 3.

In the drawing figures the dominant features of my design are shown by means of full lines.

I claim:

The ornamental design for an archery bow, as shown and described.
